DESIGN FOR A COMBINED DRILLING AND TAPPING MACHINE

Leon L. Leckinger, Los Angeles, Calif.

Application March 29, 1944, Serial No. 113,063

Term of patent 14 years

(Cl. D63—1)

To all whom it may concern:

Be it known that I, Leon L. Leckinger, a citizen of the United States of America and a resident of the city of Los Angeles, in the county of Los Angeles, and State of California, have invented a new, original, and ornamental Design for Combined Drilling and Tapping Machine, of which the following is a specification, reference being had to the accompanying drawing, forming part thereof.

In the drawing:

Figure 1 is a side elevational view of a com-

bined drilling and tapping machine, showing my new design.

Figure 2 is an end elevational view thereof.

Figure 3 is a plan view thereof.

The other side, not shown, is substantially like the side shown and the other end, not shown, is substantially plain.

I claim:

The ornamental design for a combined drilling and tapping machine, substantially as shown and described.

LEON L. LECKINGER.
